Application April 1, 1936, Serial No. 72,009

25 Claims. (Cl. 178—7.2)

This invention relates to a television transmitting system and more particularly to a system whereby pictures on a cinematographic film may be televised while the film is being constantly moved.

An object of the invention is to provide a suitable method and apparatus for scanning such film in a manner giving a standard number of lines and frames per second while utilizing commercial alternating current or other periodic actuating field as the source of power that has a frequency different from the number of frames per second desired.

Another object is to achieve interlaced scanning of a constantly moving film in a manner giving a standard number of pictures, for example, 24 frames per second, when actuated with alternating current having a frequency of 60 cycles per second.

A further object is to provide a suitable scanning oscillator for a cathode ray tube which gives a saw-toothed scanning current having cyclic irregularities.

A still further object is to provide a scanning oscillator for a cathode ray tube which gives a periodic line shifting potential whereby interlaced scanning may be practiced.

Other objects of the invention will in part be obvious and will in part appear hereinafter.

The invention accordingly comprises the several steps and the relation of one or more of such steps with respect to each of the others, and the apparatus embodying features of construction, combinations of elements and arrangements of parts, which are adapted to effect such steps, all as exemplified in the following detailed disclosure, and the scope of the invention will be indicated in the claims.

For a fuller understanding of the nature and objects of the invention reference should be had to the following detailed description taken in connection with the accompanying drawings, in which:

Fig. 1 is a view partly in perspective and partly schematic, showing a device for transmitting a facsimile of a picture on a film, in accordance with the invention;

Fig. 2 is a fragmentary view showing the manner in which interlaced scanning may be accomplished in connection with the practice of the invention;

Fig. 3 is an enlarged development of a light screen employed for regulating the admission of light to the scansion current generator which

effects the desired movement of the scanning light spot; and

Fig. 4 is a schematic view illustrating the principle by which scansion is effected of a moving film by means of the light spot moved under the control of the screen shown in Fig. 3.

The use of a so-called "intermediate film" in the process of televising a scene of action, such as a football game, for home reception or for immediate reproduction in theaters, halls, and the like, is desirable, because it obviates the limitations heretofore imposed by the available illumination.

The scansion of such a film for reproduction with standard apparatus, is in itself a problem, assuming sufficient illumination. It is now standard practice to scan pictures to be televised at 24 film frames per second, but the available actuating fields, such as commercial alternating current, for operating the television apparatus, as a rule, are standardized at some other frequency, for example, at 60 cycles per second, which is not a multiple of the number of frames desired. The operation and synchronization of standard equipment to effect the scansion of a moving film from such source of power was consequently heretofore regarded as not feasible.

By the present invention, a ready method of scansion is provided whereby a film while in motion may be scanned at the rate of 24 film frames a second and 60 field scans per second, thereby enabling commercial 60 cycle alternating current to be employed without producing moving hum patterns. To this end, a moving light spot may be employed to give a scanning beam or ray which is modulated by traversing the film to be scanned, the modulated ray resulting being projected into a suitable device that responds photoelectrically, such as a photoelectric cell, and the electric impulses had therefrom employed to modulate a carrier that is broadcast. As will be understood, the cathode ray tube employed is one form of an electronic scanning device.

By the present invention, the motion of the light spot, which may be produced in any suitable way, for example, from the illumination produced on a fluorescent screen by the impingement of a cathode ray in a cathode ray tube, is controlled and oscillated in one direction, for example, horizontally, at a relatively high frequency in order to scan line elements of the picture while it is also shifted in the other direction, that is, vertically, in an irregular manner during a prearranged cycle or period to achieve two effects, namely, first a gradual shifting of the light spot simultaneously with the

motion of the film, and second a jump of the light spot to various starting positions which takes place cyclically at irregular intervals proportioned to accommodate the commercial frequency to the number of frames to be reproduced.

The motion of the light spot is preferably not that produced by an ordinary sine-wave oscillation but that had from a saw-toothed oscillator adapted to scan a standard number of lines, for example, 342 or 343 lines per frame. In such cases, it is usual to employ interlacing. To achieve this latter in conjunction with the method of the present invention, it is proposed to send out a relatively sharp impulse with frame frequency that will effect a small shift up or down cyclically of the light spot whereby the interlaced scansion effect is had.

The means for achieving the desired movement of the light spot comprise special forms of oscillating generators that supply oscillating current to the cathode ray tube, such generators being under the control of a master device that is actuated by the commercial source of alternating current. A convenient form of master controller for this purpose utilizes photoelectric actuating means, and, to this end, has a special form of light regulating screen that is moved between the light source, or sources, as the case may be, and the photocells of the actuating means by an electric motor driven by the commercial alternating current.

Referring now to the drawings, and particularly to Fig. 1, 10 denotes a portion of the film being scanned and is shown as disposed for vertical movement and threaded over driving sprockets 11 which are driven at a suitable constant speed, by suitable means, for example, by a motor 12, shown as geared to the sprockets. A cathode ray tube 13 is arranged to provide a suitable scanning field over which the film 10 is passed and scanned by the light spot produced by the cathode ray within the tube. The light spot is focused on the vertical portion of the film by a suitable optical means, here depicted as a lens 14, the modulated light which traverses the film being picked up by another optical means, here depicted as a lens 15, and projected into a photoelectric cell 16. This latter is connected to an amplifier for modulating the carrier, generated by an oscillator 18, and coupled to an antenna 19. It will therefore be seen that the electronic scanning tube 13 is in conjugate relation with the film 10.

When the film is moved vertically downwardly, as depicted in the drawings, the scansion of the line elements of the picture is effected by moving the light spot horizontally. Accordingly, the cathode ray tube 13 is shown as provided with deflecting plates 21 and 22 disposed on opposite sides of the tube, the plates being connected to be charged by a suitable saw-toothed oscillating potential supplied by the oscillator 20.

In order to achieve vertical shifting of the light spot, as indicated above, the cathode ray tube is also provided with deflecting plates 23 and 24 in planes at right angles to the plates 21 and 22. These plates are connected to receive actuating charges from an oscillating amplifier 25, which latter is under the control of the master controlling device which comprises a screen 26 on a rotating transparent disk 27, the disk being rotated by a synchronous electric motor 28 that is supplied from standard commercial mains, here indicated as 60 cycle mains. A mask 29 is also interposed between the disk and the light source 75

30; the mask being slotted, as indicated at 29' in order to admit and sharply direct the beam of light which passes into a photoelectric cell 31; this latter being electrically connected to control

5 the amplifier 25. The light admitted to the photocell 31 is regulated by the motion past the slit 29' of a specially shaped opening 26a in the screen 26, this opening preferably having a contour of a character adapted to follow the movement of the film and give the desired oscillating current; the development of a suitable contour being depicted in Fig. 3.

In Fig. 3, the opening 26a has a base line AB, with ordinates drawn upwardly therefrom that 15 define an opening that determines the quantity and, consequently, the intensity of the light admitted; the abscissae denoting instants of the time at which the light enters with the rotation of the disk. It is thus seen that the screen may 20 be laid out on disk 27 by changing the ordinates of Fig. 3 to radii, the abscissae to circles, and the oblique lines to arcs of Archimedean spirals. The 25 serrated opening 26a operates to regulate the passage of light with the passage of time to effect sudden changes thereof to cause the shifting of the scanning light spot desired; this regulation being coordinated with the position of the picture-frame being scanned. The coordination is 30 achieved by laying off the ordinates of the opening at 26a to regulate light for actuating the oscillator in relation to the film moving events, as 35 illustrated by the relation of Fig. 3 to Fig. 4. It will, of course, be understood that the development of Fig. 3 may be applied without alteration to the surface of a revolving drum, when used as a substitute for the disk here shown.

To lay out the film moving events, a distance $x_1 - x_2$ is marked off along the time coordinate in Fig. 4 and divided into sections, each denoting 40 the period of a cycle of the series of scanning steps or events, or, what is the same thing, the period of the transit of two frames. Each transit period so marked off is not only a multiple of the period of an alternating current cycle but also 45 of a value which is the greatest common divisor of the alternating current frequency and the frame frequency. Hence, the number of frames moved times the number of transit periods in a second gives the desired number of frames per second. A suitable transit period is indicated as 50 "Period I" and "Period II," along the axis $x_1 - x_2$, and represents $\frac{1}{12}$ second and comprises five field scanning periods. This is equal to five A. C. cycles and hence moving A. C. hum patterns are 55 avoided, as will be understood. In the transit period, two frames pass completely across the field scanned, i. e., from the "full view" position where two frames are completely above the reference line to a "fully passed" position where the two frames are completely below the reference line.

During the first field-scanning period, the film will have moved from the position shown at C-1-I in the first transit period down a distance which equals $\frac{1}{12}$ ths of a frame-height at the inception of the second field-scanning period of the first transit period. This is shown at C-2-I in the drawings. At the inception of the third field-scanning period, the film will have reached a position where $\frac{1}{12}$ ths of a frame-height is below the reference line, as shown at C-3-I. At the inception of the fourth field-scanning period, $\frac{1}{12}$ ths of a frame-height is below the reference line; at the inception of the fifth field-scanning period, $\frac{1}{12}$ ths of a frame-height is below the ref-

erence line; and at the inception of the first field-scanning period of the second transit period, the two frames are fully below as shown at C—I—II.

To scan the field of the two frames, the light spot is made to traverse the field horizontally a desired number of times, for example, 342 times, or what is the same thing, with a line frequency of 10260 lines per second, giving 171 lines per field scansions. To accommodate this scansions to the constant motion of the film the light spot is permitted only sufficient upward motion to have put in the desired number of lines, when the top of the film frame, which has been moving down, is reached; in other words, to scan the lower film frame, the light spot starts from position P_1 , putting in lines and moves up only the distance h during the period of a field scansions, so as to finish at point F_1 . With the above line frequency, 171 lines will be scanned. At this juncture, the light spot is made to drop to a new starting position P_2 when it traverses the same film frame a second time during the second field-scanning period. The light spot is here permitted only sufficient upward motion to put in its 171 lines when the top of the film frame is reached, i. e., when it has moved up another distance h it finishes at point F_2 . At this juncture the light spot is again dropped to a third starting position P_3 but this time when the lower film frame has been scanned, the light spot continues upward for another field-scanning period, in order to scan the upper film frame. In other words, the finishing position F_3 for the lower film frame in the third field-scanning period is the starting position for the upper film frame in the fourth field-scanning period. At the end of the fourth field-scanning period, when the light spot has moved up a distance $2h$ from the position P_3 and has reached position F_4 , the light spot is dropped to a position P_4 where it begins to scan the upper film frame a second time. At the end of the fifth field scansions the light spot will have reached a position F_5 which corresponds to the starting position for the second transit period.

It will be seen, therefore, from Fig. 4 and the above description thereof, that a two-dimensional scanning pattern is produced by the scanning tube 13 and scans a scanning area in the path of travel of the film both laterally and longitudinally of the film in lines extending laterally thereof. During the first field-scanning period the scanning area extends longitudinally from the line beginning at P_1 to the line ending at F_1 . The height of this scanning area in the specific example of Fig. 4 is $\frac{1}{3}$ ths of the film-frame height. This scanning area is then displaced by a distance equal to $\frac{1}{6}$ ths of the film-frame height for the second field scansions, so as to begin scansions at P_2 . This displacement is therefore substantially different from the height of the scanning area that the longitudinal rate of scanning is adapted to produce in a complete field-scanning period. A similar displacement is produced between the scanning areas of field scansions 2—3 and 4—5, so that a plurality of displacements occur within a cycle. At the end of field scansions 5, the cycle begins over again. In the specific embodiment of Fig. 4, the displacements are such that the scanning areas of successive field scansions 1—2, 2—3 and 4—5, overlap by an amount equal to $\frac{1}{6}$ th of the film-frame height. Also, the longitudinal scanning is opposite to the direction of movement of the film, and the scanning area is displaced a plu-

rality of times in the direction of travel of the film within a cycle. It will also be noted that the difference between the distance the film moves in a field-scanning period ($\frac{1}{6}$ ths the film-frame height) and the height of the scanning area ($\frac{1}{3}$ ths the film-frame height) is $\frac{1}{6}$ th the height of a film frame, and hence is substantially different from the height of the scanning area.

To move and shift the light spot during the scanning periods in the manner above described, the scansion oscillator 20 is made to supply saw-toothed oscillating current of a frequency of 10260 cycles per second to the plates 21 and 22 for effecting horizontal movement. The arrangement employs a set of cascade amplifiers 33, 34 and 35 associated with the oscillator 20 which is preferably of the tube variety and overbiased, the whole being triggered off by impulses had from the photocell 37. To this end, a second light source 30 is shown emitting light controlled by a series of slots 36 laid off in the screen 26 above opening 26a. It is seen that the oscillating frequency is a harmonic of 60 and may be had from 60 cycle current impulses, provided the disk is driven by a synchronous motor driven from 60 cycle mains, as shown, and has the slots 36 on the ordinates demarking A. C. cycles on the screen 26. The design of the synchronous motor is, of course, to be considered in this connection and a proper number of poles provided. This may be readily determined with the aid of the following formula, where p denotes the number of pairs of poles to be employed, and

x , the number of transit periods on the disk

n , the revolutions per second of disk

h , the number of film frames completely scanned during a transit period

r , ($=60n$) the revolutions per minute of disk

f , the frequency of available alternating current, or actuating field

q , the film frame frequency.

Then it is seen that

$$xnh = q \text{ and } n = f/p$$

consequently

$$p = \frac{f \cdot h}{q} \cdot x \quad (1)$$

Hence for $f=60$, $h=5$ and $q=60$, Equation 1 gives

$$p=5x \quad (2)$$

Now x may be arbitrarily chosen within limits; a lower limit being $x=1$ which gives an odd number of scanning lines, for $x=2$ an even number is had. An upper limit is imposed by convenience of design. For $x=1$, Equation 2 gives $p=5$ so that $r=720$ R. P. M., whereas for $x=2$, $p=10$ and $r=360$ R. P. M.

The desired scanning frequency may be had when amplifier 33 is arranged to pick off the third harmonic of the 60 cycle impulses, giving a frequency of the 180 cycles per second. This in turn is arranged to actuate the second stage amplifier 34 from which another third harmonic may be had, i. e., the ninth harmonic of the fundamental, giving a frequency of 540 cycles per second. The third stage 35 is then arranged to give the nineteenth harmonic of the fundamental, i. e., a frequency of 10260.

The longitudinal movement of the light spot desired is effected by oscillating current supplied to the plates 23 and 24 from the oscillating amplifier 25 which has its characteristic controlled by the light admitted through opening 26a. To effect an upward movement of the light spot

through a distance h , a charging current that increases linearly is applied for $\frac{1}{60}$ th of a second. This is achieved by admitting light that increases linearly in intensity to a maximum value at the end of the first field scanning period, when it is suddenly decreased to a value giving the new starting point of the second field scanning period. To obtain this regulation of the light, the opening 26a is laid out with a base line AB, which is to be traversed by the light source in the transit period of $\frac{1}{12}$ th second corresponding to the five field scanning periods of Fig. 4. The opening is given a height AC to admit light of an intensity that gives a charge to move the light spot to position P1. An oblique line CD is drawn to effect the linear increase in the intensity of the light during the first field scanning period, this increase being terminated with an ordinate DE that drops to a point below C, in order to effect the desired drop of the light spot at the end of the first field scanning period.

From a consideration of Fig. 4, it is seen that the light intensity must be capable of being decreased by at least four units, that may be arbitrarily chosen, from that admitted by the slot 29' when restricted by the opening AC. Also, the drop in the light spot to be effected by cutting the intensity of the light to the value admitted at E, may be produced by reducing the light two units. The distance AC is then made four of these arbitrary units high; the distance EE' two units high; and the distance ED five units, since the distance h is but $\frac{3}{5}$ ths of a frame-height, or three units out of the total of four which the light spot drops.

The line EG is drawn obliquely to a point three units above E, to effect the upward movement of the light by another distance h and then terminated with an ordinate reaching to a point H in the base line AB. From H an oblique line is drawn to K which spans a distance equal to two A. C. cycles, the point K being six units above the base line. This permits the light spot to scan the lower film frame in the third field scanning period and to continue with the scansion of the upper film frame during the fourth field scanning period.

The ordinate KM terminates the line HK at the end of the fourth field scanning period and drops the light spot for the second scansion of the upper film frame by decreasing the light admitting opening to a value one unit high, denoted by MM'. From M an oblique line MN is drawn in which N is three units higher than point M, in order to increase the regulating light in intensity sufficiently to effect another upward movement of the light spot by a distance h . The point N terminates that portion of the opening 26a which corresponds to Period I in Fig. 4; this contour being repeated in cycles corresponding to each transit period. The contour of a transit period in Fig. 3 is, of course, laid off in sectors on disk 26; the number of sectors being at least two where interlacing is practiced, as hereinafter more fully explained.

To achieve interlaced scanning, the light spot is given a small shift up (or down, as the case may be) equal to half the width of a scanned line with every other field scanned. This is effected by generating a flat topped line shifting current of field frequency, which, in this case, is 60 cycles per second; such current being applied to the plates 23 and 24 along with the light spot shifting current from amplifier 25. This current is generated by providing a series of rectangular

openings, each of the duration of a field-scanning period, in the light screen 26, as shown at 39 in Figs. 1 and 3; the openings being shown by way of example as placed below both the opening 26a and slots 36. In Fig. 3, such openings have a base line A'B' corresponding to a transit period in length, each opening being of constant width and of a length equal to one field-scanning period. They admit light from a source 30" that is projected into a photocell 40 that is connected to an amplifier 41 which generates the desired line shifting current. By this means, the second scansion of the lower film frame does not have the lines put in the same as in the scansion effected during the first field-scanning period, but is shifted to start at a point between lines, as shown in Fig. 2, where the series of lines put in, in the lower film frame during the first field-scanning period are denoted a. The shifting potential which retains the light spot in the a position is generated by regulating light, admitted by the opening at a' in Fig. 3. A second series of lines, denoted b, are thereafter put in, in the second field-scanning period, by the shutting off of regulating light by the block b' in Fig. 3. In the third field-scanning period, opening a'' admits regulating light to cause a shift that again puts in the a series of lines in the lower frame of Fig. 2, the block b'' causing a shift that puts in a series of lines b in the upper frame of Fig. 2 during the fourth field-scanning period. After this, the opening a''' admits regulating light that puts in a series of lines a in the upper frame of Fig. 2. From this, it is seen that Period II is not started by putting in a series of lines a, as was Period I, but instead by putting in lines b. Periods I and II are thus complementary and have alternatively different starting points.

In the drawings, it is seen that conductors 42 and 43 are provided to impress on the carrier oscillator 18 impulses from saw-toothed wave generator 20 and line shifting amplifiers 25 and 41 in order that they may be broadcast with the picture signal for synchronizing purposes.

In operation, it is seen that the film 10 is caused to move downwardly at a constant rate across the scanning light spot on the end of tube 13, which spot is gradually moved upwardly against the motion of the film and then dropped to a new starting position at recurring intervals. The modulated light resulting is projected into photocell 16 to modulate the carrier that is broadcast from the antenna 19.

The light spot produced by a cathode ray is moved by deflecting the cathode ray horizontally by deflecting plates 21 and 22 with saw-toothed current of a frequency of 10260 cycles per second had from 60 cycle impulses optically produced. Plates 23 and 24 produce a vertical shift that takes place gradually upward and suddenly downward at intervals of $\frac{1}{60}$ th of a second by means of impulses that change every $\frac{1}{60}$ th of a second and are optically produced by the opening 26a.

From the arrangement shown, it is seen that while the effect is to scan 24 film frames each second, there are actually 60 fields scanned per second, the film frames being scanned in pairs during the transit period which is $\frac{1}{12}$ th of a second in duration. During this period one film frame of the pair traversing the scansion field is scanned three times while the other is scanned twice. In this way, the desired standard number of film frames may be transmitted and reproduced at the receiving station. At the re-

ceiving station, the scansion may be effected by the same method as in transmitting and the picture viewed directly on a fluorescent screen of a receiving cathode ray tube, or another film may be exposed to the image on the tube while being moved continuously and synchronously with that at the transmitter. The film thus made is developed and projected on a viewing screen.

Where it is desired to execute interlaced scansion of a field with 343 lines or 171½ lines per field scansion, the saw-toothed oscillator 20 is arranged to supply oscillating current of a frequency of 10290, the screen 26 being suitably perforated to achieve this. As a result, it is seen that a field scansion is either begun or ended with a half line so that the light spot is already shifted to another starting position without the use of openings 39, as will be readily understood.

The oscillating amplifiers 25 and 41, while arranged to give only 60 cycle currents, should, of course, be designed to handle currents of very much higher frequency in order to have a safe margin for operation with constancy and fidelity. For example, such amplifiers may be made to accommodate frequencies of 6000 cycles per second.

The optical system of the scansion current generator, comprising light source, slit 29', opening in screen 26 and photocell, may, of course, and preferably does include one or more lens systems, the showing of such being omitted from the drawings in the interest of simplicity and clearness of illustration. Such system may also include one or more alignment adjusting means, associated with its elements, such as a micrometer screw, applied in a manner well known in the optical art. The slit 29' in such case has each controlling part independently adjustable in a lateral direction and may also be adjustable in width, such devices being employed in the interests of refinement and precision but in no way affecting the principles of the invention as herein set forth.

Also, it will be seen that other sets of slots may be provided on the oscillation generator disk for producing other characteristics in the scansion current supplied, for example, a set of slots may be provided additionally for extinguishing the light spot during the back stroke as it returns to start another line.

Since certain changes in carrying out the above process and in the constructions set forth which embody the invention may be made without departing from its scope, it is intended that all matter contained in the above description or shown in the accompanying drawings shall be interpreted as illustrative and not in a limiting sense.

Having described my invention what I claim as new and desire to secure by Letters Patent is:

1. Apparatus for scanning a picture film in facsimile transmission comprising, in combination, means including a cathode ray tube having a screen impinged by a cathode ray to provide a scansion field having a scanning light spot over which the film is moved, means including an actuating field for continuously moving said film over said scansion field at a rate which passes a desired number of frames in a period which is a multiple of an actuating field cycle, a tube oscillator for supplying current to said cathode ray tube for deflecting the cathode ray in a direc-

tion and at a frequency suitable for line scanning, a second tube oscillator for supplying current to said cathode ray tube for shifting said ray so as to advance over the film during said film motion in a manner which completes the scanning of a frame in a desired period, photoelectric devices for actuating said oscillators, a moving light regulating screen for said photoelectric devices, and means for moving said screen under the control of said actuating field; the regulation of said screen being correlated with the frequency of said actuating field to give a scanning effect at a standard frame frequency.

2. Apparatus for scanning a picture film in facsimile transmission comprising, in combination, means including a cathode ray tube having a screen impinged by a cathode ray to provide a field having a scanning light spot over which the film is moved, means including an alternating current motor for continuously moving said film over said field at a rate which passes a desired number of frames in a period which is a multiple of an A. C. cycle, a tube oscillator for supplying current to said cathode ray tube for deflecting the cathode ray in a direction and at a frequency suitable for line scanning, a second tube oscillator for supplying current to said cathode ray tube for shifting said ray so as to advance over the film during said film motion in a manner which completes the scanning of a frame in a desired period, a controlling photoelectric cell connected to each of said oscillators, a light screen having an opening with a recurring pattern for regulating the light admitted to each of said photoelectric cells, and an alternating current motor for moving said screen at a rate which causes said oscillators to generate currents having frequencies that are harmonics of the alternating current frequency.

3. Apparatus for scanning a picture film in facsimile transmission comprising, in combination, means including a cathode ray tube having a screen impinged by a cathode ray to provide a field having a scanning light spot over which the film is moved, means including an alternating current motor for continuously moving said film over said field at a rate which passes a desired number of frames in a period which is a multiple of an A. C. cycle, a tube oscillator for supplying current to said cathode ray tube for deflecting the cathode ray in a direction and at a frequency suitable for line scanning, a second tube oscillator for supplying current to said cathode ray tube for shifting said ray so as to advance over the film during said film motion in a manner which completes the scanning of a frame in a desired period, a controlling photoelectric cell connected to each of said oscillators, a light screen having a continuous opening of a recurrent serrated pattern for regulating the light to the photoelectric cell controlling the line shifting oscillator and a series of discontinuous openings for controlling the line scanning oscillator, and a synchronous alternating current motor for moving said light screen and having its poles chosen to impart motion at a rate which effects a desired correlation between said oscillators and the alternating current frequency.

4. Apparatus for scanning a picture film in facsimile transmission comprising, in combination, means including a cathode ray tube having a screen impinged by a cathode ray to provide a field having a scanning light spot over which the film is moved, means including an alternating current motor for continuously moving said film

over said field at a rate which passes a desired number of frames in a period which is a multiple of an A. C. cycle, a tube oscillator for supplying current to said cathode ray tube for deflecting the cathode ray in a direction and at a frequency suitable for line scanning, a second tube oscillator for supplying current to said cathode ray tube for shifting said ray so as to advance over the film during said film motion in a manner which completes the scanning of a frame in a desired period, a third tube oscillator for supplying a shifting potential with the scansion of alternate frames whereby interlaced scansion may be effected, a controlling photoelectric cell connected to each of said oscillators, a light screen having a series of equally spaced openings occurring at predetermined intervals that regulate the light to the cell of said first tube oscillator, a continuous serrated opening arranged to regulate the light to the cell of said second tube oscillator, another series of openings that regulate the light to the cell of said third tube oscillator, and a synchronous alternating current motor having its pairs of poles chosen in number such as to move said screen at a rate which gives an oscillating current that scans the frames with a frequency that is a multiple of the available alternating current frequency and shifts across frames and effects interlacing with a frequency based on the alternating current frequency.

5. In television scanning systems, apparatus for energizing the deflecting means of a cathode ray tube which comprises, in combination, a tube oscillator adapted to supply the oscillating current, a photoelectric cell connected to control said oscillator, a screen having an opening of an irregular serrated pattern for admitting light to said cell, said irregularity in the pattern recurring cyclically, and a synchronous alternating current motor for rotating said screen.

6. Apparatus for scanning a picture film in facsimile transmission comprising, in combination, a means including a cathode ray tube having a screen impinged by a cathode ray to provide a field having a scanning light spot over which the film is moved, means including an alternating current motor for continuously moving said film over said field at a rate which passes a desired number of frames in a period which is a multiple of an A. C. cycle, a tube oscillator for supplying current to said cathode ray tube for deflecting the cathode ray at a frequency of 10,260 cycles per second and in a direction suitable for line scanning, a connected series of cascaded amplifiers supplying respectively the 19th, 9th and 3rd harmonics, a second tube oscillator for supplying current to said cathode ray tube for shifting said ray so as to advance over the film during said film motion in a manner which completes the scanning of a frame in a desired period, a controlling photoelectric cell adapted to trigger off the 3rd harmonic amplifier and a second controlling photoelectric cell connected to said second oscillator, a light screen having a continuous opening of a recurrent serrated pattern for regulating the light to the second mentioned photoelectric cell controlling the line shifting oscillator and a series of discontinuous openings for controlling light impulses into the first mentioned photoelectric cell at a 60 cycle fundamental frequency for controlling the line scanning oscillator, and a synchronous alternating current motor for moving said light screen and having its poles chosen to impart motion at a rate which

75 effects a desired correlation between said oscillators and the alternating current frequency.

7. Apparatus for scanning a picture film in facsimile transmission comprising, in combination, 5 means including a cathode ray tube having a screen impinged by a cathode ray to provide a scansion field having a scanning line spot over which the film is moved, means including an actuating field for continuously moving said film over said scansion field at a rate which passes a desired number of frames in a period which is a multiple of an actuating field cycle, means for deflecting the cathode ray in a direction and at a frequency suitable for line scanning, a tube oscillator for supplying current to said cathode ray tube for shifting said ray so as to advance over the film during said film motion in a manner which completes the scanning of a screen in a desired period, a photoelectric cell connected to control said oscillator, a screen having an opening of an irregular serrated pattern for admitting light to said cell, said irregularity in the pattern recurring cyclically, and a synchronous alternating current motor under the control of said actuating field for rotating said screen, the light regulation produced by said screen being correlated with the frequency of said actuating field to give a scanning effect at a standard frame frequency.

8. Television film-scanning apparatus which comprises a film-feeding mechanism adapted to feed a film longitudinally at a uniform speed and selected film-frame frequency, a scanning device positioned and associated in cooperative relation with said film-feeding mechanism, means associated with said scanning device for producing a two-dimensional scanning pattern of field-scanning frequency adapted to scan a scanning area in the path of travel of said film both laterally and longitudinally of said film in lines extending laterally thereof, said field-scanning frequency being different from said film-frame frequency, and means for cyclically and successively associating the scanning pattern with scanning areas in the path of travel of the film having a plurality of respective displacements in the same direction within a cycle, said displacements with respect to the scanning areas of the corresponding immediately preceding field 45 scancings being substantially different from the height of the scanning area that the longitudinal rate of scanning is adapted to produce in a complete field-scanning period and being selected to compensate for film movement and cause field 50 scancings to register with respective film frames.

9. Television film-scanning apparatus which comprises a film-feeding mechanism adapted to feed a film longitudinally at a uniform speed and selected film-frame frequency, a scanning device positioned and associated in cooperative relation with said film-feeding mechanism, means associated with said scanning device for producing a two-dimensional scanning pattern of field-scanning frequency adapted to scan a scanning area in the path of travel of said film both laterally and longitudinally of said film in lines extending laterally thereof, said field-scanning frequency being different from said film-frame frequency, and means for cyclically and successively associating the scanning pattern with scanning areas in the path of travel of the film having a plurality of respective displacements in the same direction within a cycle, said displacements being selected to cause corresponding scanning areas to overlap respective immediately

preceding scanning areas by a substantial amount and to compensate for film movement and cause field scensions to register with respective film frames.

10. Television film-scanning apparatus which comprises a film-feeding mechanism adapted to feed a film longitudinally at a uniform speed and selected film-frame frequency, a scanning device positioned and associated in cooperative relation with said film-feeding mechanism, means associated with said scanning device for producing a two-dimensional scanning pattern of field-scanning frequency adapted to scan a scanning area in the path of travel of said film both laterally and longitudinally of said film in lines extending laterally thereof, said field-scanning frequency being different from said film-frame frequency and the longitudinal scanning being opposite to the direction of movement of the film, and means for cyclically and successively associating the scanning pattern with scanning areas in the path of travel of the film having a plurality of respective displacements, with respect to the scanning areas of the corresponding immediately preceding field scensions, in the direction of travel of the film within a cycle, the displacements between said scanning areas being selected to compensate for film movement and cause field scensions to register with respective film frames.

11. Television film-scanning apparatus which comprises a film-feeding mechanism adapted to feed a film longitudinally at a uniform speed and selected film-frame frequency, an electronic scanning device positioned and associated in cooperative relation with said film-feeding mechanism, means associated with said electronic scanning device for producing a two-dimensional scanning pattern of field-scanning frequency adapted to scan a scanning area in the path of travel of said film both laterally and longitudinally of said film in lines extending laterally thereof to thereby scan a film frame, said field-scanning frequency being higher than said film-frame frequency whereby at least some film frames are scanned in a plurality of field scensions, the longitudinal scanning being opposite to the direction of movement of the film and the difference between the distance the film moves in a field-scanning period and the height of a scanning area that the longitudinal rate of scanning is adapted to produce in a complete field-scanning period being substantially different from said height, and means for cyclically and successively associating the scanning pattern with scanning areas in the path of travel of the film having a plurality of respective displacements within a cycle, with respect to the scanning areas of the corresponding immediately preceding field scensions, which are substantially different from the height of the scanning area that the longitudinal rate of scanning is adapted to produce in a complete field-scanning period, said plurality of displacements being selected to compensate for film movement and cause field scensions to register with respective film frames, said means for producing a two-dimensional scanning pattern and said displacements being correlated to scan different interlaced sets of lines of the film frames which are scanned in a plurality of field scensions.

12. Television film-scanning apparatus which comprises a film-feeding mechanism constructed and adapted to feed a film at a uniform speed of substantially 24 film-frames per second, a scan-

ning device positioned and associated in cooperative relation with said film-feeding mechanism, means associated with said scanning device for producing a two-dimensional scanning pattern having a field frequency of substantially 60 fields per second and adapted to scan a scanning area in the path of travel of the film both laterally and longitudinally of the film in lines extending laterally thereof, the longitudinal scanning being opposite to the direction of movement of the film and the longitudinal length of said scanning area being selected to traverse a film frame in a field-scanning period, and means for cyclically and successively associating the scanning pattern with scanning areas in the path of travel of the film having a plurality of respective displacements within a cycle, with respect to the scanning areas of the corresponding immediately preceding field scensions, which are substantially different from the height of the scanning area that the longitudinal rate of scanning is adapted to produce in a complete field-scanning period, said plurality of displacements being selected to compensate for film movement and cause said scanning area to register three times with alternate film frames and twice with the film frames therebetween.

13. In a television transmitter, film-scanning apparatus which comprises a film-feeding mechanism adapted to feed a film longitudinally at a uniform speed and selected film-frame frequency, a scanning device positioned and associated in cooperative relation with said film-feeding mechanism, means associated with said scanning device for producing a two-dimensional scanning pattern of field-scanning frequency adapted to scan a scanning area in the path of travel of said film both laterally and longitudinally of said film in lines extending laterally thereof, said field-scanning frequency being higher than said film-frame frequency and the longitudinal scanning being opposite to the direction of movement of the film, and means for cyclically and successively associating the scanning pattern with scanning areas in the path of travel of the film having a plurality of respective displacements within a cycle in the direction of movement of the film, said plurality of displacements being selected to cause corresponding scanning areas to overlap respective immediately preceding scanning areas by a substantial amount and to compensate for film movement and cause field scensions to register with respective film frames.

14. The method of scanning a film in television transmission which comprises feeding a film uniformly at a selected film-frame frequency, successively scanning two-dimensional scanning areas in the path of travel of the film laterally and longitudinally in laterally extending lines at a selected field-scanning frequency different from said film-frame frequency to thereby scan respective film frames of the film, and cyclically shifting the scanning area for successive field scensions by a plurality of displacements in the same direction within a cycle, with respect to the scanning areas of respective immediately preceding field scensions, which are substantially different from the height of the scanning area that the longitudinal rate of scanning is adapted to produce in a complete field-scanning period, said plurality of displacements being correlated with the film-frame frequency and the field-scanning frequency to compensate for film movement and cause field scensions to register with respective film frames.

15. The method of scanning a film in television transmission which comprises feeding a film at a uniform speed and selected film-frame frequency, successively scanning two-dimensional scanning areas in the path of travel of the film laterally and longitudinally to scan corresponding laterally extending interlaced sets of lines of respective film frames, the field frequency of the scanning of said areas being higher than the film-frame frequency and the longitudinal scanning being opposite to the direction of movement of the film, and cyclically shifting the scanning area for successive field scansions by a plurality of displacements within a cycle, with respect to the scanning areas of respective immediately preceding field scansions, which are substantially different from the height of the scanning area that the longitudinal rate of scanning is adapted to produce in a complete field-scanning period, said plurality of displacements being correlated with the film-frame frequency and the field-scanning frequency to compensate for film movement and cause field scansions to register with respective film frames.

16. The method of scanning a film in television transmission which comprises feeding a film at a uniform speed and selected film-frame frequency, successively scanning two-dimensional scanning areas in the path of travel of the film laterally and longitudinally in laterally extending lines at a selected field-scanning frequency higher than said film-frame frequency to thereby scan respective film-frames, the longitudinal scanning of said areas being opposite to the direction of movement of the film and the difference between the distance the film moves in a field-scanning period and the height of a scanning area that the longitudinal rate of scanning is adapted to produce in a complete field-scanning period being substantially different from said height, and cyclically shifting the scanning area for successive field scansions by a plurality of displacements within a cycle, with respect to the scanning areas of respective immediately preceding field scansions, which are substantially different from the height of the scanning area that the longitudinal rate of scanning is adapted to produce in a complete field-scanning period, said plurality of displacements being correlated with the film-frame frequency and the field-scanning frequency to compensate for film movement and cause field scansions to register with respective film frames.

17. The method of scanning a film in television transmission which comprises feeding a film at a uniform speed of substantially 24 film-frames per second, successively scanning two-dimensional scanning areas in the path of travel of the film laterally and longitudinally in laterally extending lines at a field-scanning frequency of substantially 60 fields per second, the longitudinal scanning of said areas being opposite to the direction of movement of the film and the longitudinal length of each area being sufficient to traverse a film frame in the respective field-scanning period, and cyclically shifting the scanning area for successive field scansions by a plurality of displacements within a cycle with respect to the scanning areas of respective immediately preceding field scansions, said displacements being substantially different from the height of the scanning area that the longitudinal rate of scanning is adapted to produce in a complete field-scanning period and being selected to compensate for film movement and cause said scanning area

to register three times with alternate film frames and twice with the film frames therebetween.

18. The method of scanning a film in television transmission which comprises feeding a film at a uniform speed and selected film-frame frequency, successively scanning two-dimensional scanning areas in the path of travel of the film laterally and longitudinally in laterally extending lines at a selected field-scanning frequency higher than said film-frame frequency to thereby scan respective film-frames, the longitudinal scanning of said areas being opposite to the direction of movement of the film, and cyclically and successively shifting the scanning area in the path of travel of the film by a plurality of displacements within a cycle in the direction of movement of the film, said displacements being selected to cause corresponding scanning areas to overlap respective immediately preceding scanning areas by a substantial amount and to compensate for film movement and cause field scansions to register with respective film frames.

19. In electronic film-scanning apparatus, the combination which comprises an electronic scanning device, a film-feeding mechanism positioned to support a film in cooperative relation with said scanning device and adapted to feed the film longitudinally at a uniform speed, means associated with said scanning device for scanning said film at line-scanning frequency in lines extending laterally of the film, deflection means associated with said scanning device for deflecting an electronic beam therein to scan said film longitudinally, means for cyclically producing a plurality of successive longitudinal scanning waves which change abruptly from respective final values to a plurality of substantially different initial values within a cycle, each of said plurality of waves extending throughout at least one field-scanning period and changing gradually from an initial value to a final value, and means for impressing said longitudinal scanning waves on said deflection means to thereby produce two-dimensional scanning patterns successively associated with a plurality of scanning areas in the path of travel of the film, said different initial values being selected to associate said two-dimensional scanning patterns with scanning areas having a plurality of respective displacements in the same direction within a cycle.

20. In electronic film-scanning apparatus wherein film frames are scanned at a field frequency different from the film-frame frequency, the combination which comprises a film-feeding mechanism constructed and adapted to feed a film longitudinally at a uniform speed and selected film-frame frequency, an electronic scanning device positioned in cooperative conjugate relation with the film in said mechanism, means associated with said scanning device for scanning said film at line-scanning frequency in lines extending laterally of the film, deflection means associated with said scanning device for scanning said film longitudinally, means for cyclically producing a plurality of successive longitudinal sawtooth-scanning waves each extending throughout at least one field-scanning period and having a plurality of substantially different initial values within a cycle, and means for applying said longitudinal sawtooth-scanning waves to said deflection means to thereby produce two-dimensional scanning patterns successively associated with a plurality of scanning areas in the path of travel of the film during respective field scanning

periods, the field frequency of said sawtooth-scanning waves being different from said film-frame frequency and the waves being applied to said deflection means to produce longitudinal scanning of said scanning areas opposite to the direction of movement of the film, said different initial values being selected to associate said two-dimensional scanning patterns with scanning areas having a plurality of respective displacements in the same direction within a cycle.

21. In electronic film-scanning apparatus wherein film frames are scanned at a field frequency higher than the film-frame frequency, the combination which comprises an electronic scanning device, a film-feeding mechanism positioned to support a film in cooperative relation with said scanning device and adapted to feed the film longitudinally at a uniform speed and selected film-frame frequency, means associated with said scanning device for scanning said film at line-scanning frequency in lines extending laterally of the film, deflection means associated with said scanning device for deflecting an electronic beam therein to scan said film longitudinally, means for cyclically producing a plurality of successive longitudinal sawtooth-scanning waves which change abruptly from respective final values to a plurality of substantially different initial values within a cycle, each of said plurality of waves extending throughout at least one field-scanning period, and means for impressing said sawtooth-scanning waves on said deflection means to scan the film opposite the direction of movement thereof during the field-scanning periods, the field-scanning frequency being higher than said film-frame frequency and the difference between the distance the film moves in a field-scanning period and the height of a scanning area at the film which the longitudinal rate of scanning is adapted to produce in a complete field-scanning period being substantially different from said height, said plurality of different initial values being selected to compensate for the film movement and cause successive field scans to register with respective film-frames.

22. In electronic film-scanning apparatus, the combination which comprises an electronic scanning device, a film-feeding mechanism positioned to support a film in cooperative relation with said scanning device and adapted to feed a film longitudinally at a uniform speed, means associated with said scanning device for scanning said film at line-scanning frequency in lines extending laterally of the film, deflection means associated with said scanning device for scanning said film longitudinally, means for cyclically producing a plurality of successive longitudinal sawtooth-scanning waves each extending throughout at least one field-scanning period and having a plurality of substantially different initial values, and means for applying said longitudinal sawtooth-scanning waves to said deflection means to thereby produce two-dimensional scanning patterns successively associated with a plurality of scanning areas in the path of travel of the film during respective field scanning periods, the field frequency of said longitudinal sawtooth-scanning waves being higher than said film-frame frequency and the waves being applied to said deflection means to produce longitudinal scanning of said scanning areas opposite to the direction of movement of the film, said different initial values being selected to associate said two-dimensional scanning patterns with scanning areas

5 in the path of travel of the film having a plurality of respective displacements within a cycle in the direction of movement of the film and to compensate for film movement and cause field scans to register with respective film frames.

23. In electronic film-scanning apparatus, the combination which comprises an electronic scanning device, a film-feeding mechanism positioned to support a film in cooperative relation with said scanning device and adapted to feed a film longitudinally at a uniform speed, means associated with said scanning device for scanning said film at line-scanning frequency in lines extending laterally of the film, deflection means associated with said scanning device for scanning said film longitudinally, means for cyclically producing a plurality of successive longitudinal sawtooth-scanning waves each extending throughout at least one field-scanning period and having a plurality of substantially different initial values, and means for applying said longitudinal sawtooth-scanning waves to said deflection means to thereby produce two-dimensional scanning patterns successively associated with a plurality of scanning areas in the path of travel of the film during respective field-scanning periods, the field frequency of said longitudinal sawtooth-scanning waves being higher than said film-frame frequency and the waves being applied to said deflection means to produce longitudinal scanning of said scanning areas opposite to the direction of movement of the film, said different initial values being selected to associate said two-dimensional scanning patterns with scanning areas in the path of travel of the film having a plurality of respective displacements within a cycle in the direction of movement of the film and being correlated with the longitudinal field scanning to cause a plurality of scanning areas to overlap by a substantial amount, whereby film movement may be compensated and field scans registered with respective film frames.

24. In electronic film-scanning apparatus, the combination which comprises a film-feeding mechanism constructed and adapted to feed a film at a uniform speed of substantially 24 film frames per second, an electronic scanning device positioned in cooperative conjugate relation with the film in said mechanism, means associated with said scanning device for scanning said film at line-scanning frequency in lines extending laterally of the film, deflection means associated with said scanning device for scanning said film longitudinally, means for cyclically producing a plurality of successive longitudinal sawtooth-scanning waves each extending throughout at least one field-scanning period and having a plurality of substantially different initial values to thereby produce scanning patterns occupying a plurality of non-contiguous positions in the path of travel of the film within a cycle, and means for applying said sawtooth-scanning waves to said deflection means, the field frequency of said sawtooth-scanning waves being substantially 60 fields per second and said plurality of different initial values being selected to compensate for film movement and cause said scanning patterns to register three times successively with alternate film frames and twice successively with the film frames therebetween, said means for scanning the film at line-scanning frequency and said longitudinal sawtooth-scanning waves being correlated to scan a plurality of different interlaced sets of lines of each film

frame during respective field scansions of the film frame.

25. In a television transmitter, apparatus for scanning a continuously moving film at a field frequency higher than and a non-multiple of the film-frame frequency which comprises a film-feeding mechanism adapted to feed a film longitudinally at a uniform speed and selected film-frame frequency, a scanning device positioned and associated in cooperative relation with said film-feeding mechanism, means associated with said scanning device for producing a two-dimensional scanning pattern of field-scanning frequency adapted to scan a scanning area in the path of travel of said film both laterally and longitudinally of said film in lines extending lat-

erally thereof, said field-scanning frequency being higher than and a non-multiple of said film-frame frequency and the longitudinal scanning being opposite to the direction of movement of the film, and means for cyclically and successively associating the scanning pattern with scanning areas in the path of travel of the film having a plurality of respective displacements within a cycle in the direction of movement of the film, said plurality of displacements being selected to cause corresponding scanning areas to overlap respective immediately preceding scanning areas by a substantial amount and to compensate for film movement and cause field scansions to register with respective film frames.

PETER C. GOLDMARK.
